CLAIM

The ornamental design for a portable water bottle, as shown and described.

DESCRIPTION

FIG. 1 is a perspective view of a portable water bottle showing our new design;

FIG. 2 is a front elevational view of the portable water bottle; FIG. 3 is a left side elevational view of the portable water bottle;

FIG. 4 is a left side elevational view of the portable water bottle;

FIG. 5 is a rear elevational view of the portable water bottle; FIG. 6 is a top plan view of the portable water bottle; and, FIG. 7 is a bottom plan view of the portable water bottle.

The broken lines in the drawing depict portions of the portable water bottle that form no part of the claimed design.
